UNITED STATES PATENT OFFICE.

CORNEALIUS WELKER RUSSELL, OF BURLINGTON, IOWA.

OIL-BURNER.

1,260,457.

Specification of Letters Patent. Patented Mar. 26, 1918.

Application filed November 21, 1917. Serial No. 203,227.

To all whom it may concern:

Be it known that I, CORNEALIUS W. RUSSELL, a citizen of the United States, residing at Burlington, in the county of Des Moines and State of Iowa, have invented a new and useful Oil-Burner, of which the following is a specification.

This invention relates to oil and gas burners particularly designed for use in connection with heating furnaces, one of the objects of the invention being to provide means whereby an extensive gas flame can be produced extending over a considerable area, the flame being so located as to be especially useful in heating the fire pot of a hot air furnace, or a hot water or steam furnace or similar structure.

A still further object is to provide means whereby the size of the flame can be readily controlled, the burner consisting of a series of vaporizing chambers which can be placed successively into operation thus to increase the size of the flame and the heating capacity of the furnace at will.

25 A further object is to provide a burner which can be manufactured cheaply, can be easily installed, and which by supplying air to the flame requires the minimum amount of oil fuel.

30 With the foregoing and other objects in view which will appear as the description proceeds, the invention resides in the combination and arrangement of parts and in the details of construction hereinafter described

35 and claimed, it being understood that changes in the precise embodiment of the invention herein disclosed, can be made within the scope of what is claimed, without departing from the spirit of the invention.

40 In the accompanying drawings the preferred form of the invention has been shown.

In said drawings:—

Figure 1 is a central vertical section through a burner embodying the present improvements.

Fig. 2 is a section on line 2—2 of Fig. 1.

Referring to the figures by characters of reference A designates a portion of the grate of a furnace and mounted on this 50 grate is a tubular core 1 the lower end of which is screw-threaded and engaged by a cap 2 constituting the base of the burner. Another cap 3 is screwed onto the upper end of the core and serves to close said end.

55 The core is provided with external screw-threads at intervals as shown at 4 and

mounted on the core are superposed pairs of concavo-convex disks, each pair including a lower large disk 5 and an upper smaller disk 6. The lower disk constitutes a fuel container while the upper disk is oppositely disposed and constitutes a hood, the peripheral portions of the two disks being slightly separated, thus to form an unbroken or continuous annular slit or opening 7 serving as a vent for the generated gas. Each of the disks has an internally screw-threaded hub 8 and these hubs engage the adjacent threaded portions 4 on the core 1. Obviously the disks, by being independently rotated, can be adjusted toward or from each other, thus to regulate the size of the slit 7 between them.

Extending into the core 1 from the bottom thereof are fuel supply pipes 9 and these pipes open into the spaces between the disks of the respective pairs, each pipe being provided with a controlling valve 10. In the present instance four pairs of disks have been illustrated and, consequently, four fuel supply pipes have been provided, each pipe having a valve 10.

Opening into the bottom of the core 1 is an air supply pipe 11 having a valve 12. Air outlet ports 13 are formed in the core 85 close to each of the upper disks 6, these outlet openings being adapted to direct air into the flame of the burning oil directly under said disks, thereby to produce an intense heat.

It is to be understood that when a burner such as described is in position within a furnace, the peripheral portions of the disks 5 and 6 will be supported close to the wall of the fire pot. When it is desired to use the 95 burner fuel is first admitted through one of the pipes 9 into the lowermost disk 5. This fuel is ignited and the air and gas forms a gas flame which flows through the annular slit or opening 7 and the heat generated will 100 result in the vaporization of all fuel contained upon the lowermost disk 5 and will also result in heating all of the disks above the fuel as well as in heating the wall of the fire pot. Thus ultimately the gas generated between the lowermost pair of disks 5 and 6 will mingle with air supplied thereto through the lowermost openings or ports 13, thereby forming a highly combustible gas, which will burn with an intense heat at the 110 outlet 7. When it is desired to increase the heating capacity of the burner additional

fuel is directed into the disk 5 next above the pair of disks in which gas is being generated and as this disk 5 has been heated to a high temperature, the fuel will be vaporized promptly and will mix with air and discharge as a gas at the annular opening 7 where it will be ignited and thus add to the size of the flame. The flame can be further increased in size by directing fuel into the next highest disk 5 or into all of the disks, gas being generated at each of these points and becoming ignited at the annular openings 7. Oil at no time flows from the openings 7.

15 Should the parts require cleaning they can be readily unscrewed from the core 1 and subsequently replaced.

It will be seen that a burner such as described can be cheaply manufactured.

20 What is claimed is:—

1. A burner including an upstanding tubular core having an air inlet, superposed pairs of disks mounted on the core, the disks of each pair being oppositely disposed and spaced apart to form an annular slit, there being ports in the core for directing air from the core into the spaces between the disks of the respective pairs, and means for directing oil in controlled quantities into the 30 spaces between the disks of the respective pairs.

2. A burner including a tubular core, superposed pairs of disks upon the core, the disks of each pair being oppositely disposed and spaced at their peripheries to form a 35

gas outlet, said disks being adjustably mounted upon the core and relative to each other, and means for supplying oil in controlled quantities to the spaces between the disks of the respective pairs.

3. A burner including a tubular core, superposed pairs of disks upon the core, the disks of each pair being oppositely disposed and spaced at their peripheries to form a gas outlet, said disks being adjustably 45 mounted upon the core and relative to each other, and means for supplying oil in controlled quantities to the spaces between the disks of the respective pairs there being means for directing air from the core and 50 into said spaces to mix with generated gas.

4. An oil burner including a tubular core having a valved air inlet, superposed pairs of disks mounted on the core, the disks of each pair being oppositely disposed and 55 spaced apart at their peripheries to form gas outlets, there being ports for directing air from the core and into the spaces between the disks of the respective pairs, and means for directing oil into said spaces between the disks, said means including controlling valves.

In testimony that I claim the foregoing as my own, I have hereto affixed my signature in the presence of two witnesses.

CORNEALIUS WELKER RUSSELL.
